UNITED STATES PATENT OFFICE.

JEAN COTAL, OF PUTEAUX, FRANCE.

CHANGE-SPEED-GEAR MECHANISM.

Application filed June 28, 1920. Serial No. 892,459.

(GRANTED UNDER THE PROVISIONS OF THE ACT OF MARCH 3, 1921, 41 STAT. L., 1313.)

To all whom it may concern:

Be it known that I, JEAN COTAL, a citizen of the Republic of France, residing at Puteaux, France, have invented new and useful Improvements in Change-Speed-Gear Mechanisms, for which I filed an application in France January 11, 1917, No. 499,476, and Great Britain, July 31, 1919, No. 135,450, of which the following is a specification.

10 This invention relates to improvements in change speed gears, the object of the invention being to provide improved apparatus of this kind which enables four forward speeds to be obtained, and also allows braking and a rear speed to be obtained by electrically operated means, and which also provides mechanically operated means for driving in first speed in the event that the electric power fails.

20 With the above and other objects in view, the invention consists in the construction, combination and arrangement of devices hereinafter described and claimed.

In the accompanying drawing:—

25 Fig. 1 is an axial longitudinal section of the mechanism; and

Fig. 2 is a cross section showing specially the mechanic control.

The apparatus comprises a primary shaft 30 A secured to the driving shaft and which rotates, accordingly, at same speed as said shaft, and two intermediary shafts B and C parallel to shaft A, mounted on a plate D keyed on shaft A. Said shafts B and C 35 may rotate freely in bearings carried by the plate, as shown in Fig. 1.

The mechanism is enclosed in a cylindrical casing a and on one of the flat bottoms of the latter are fixed two electro-magnets 40 E and F. Two other electro-magnets G and H are fixed on secondary shaft K and carried by a plate k which is connected to said shaft.

A commutator may send an electric current to magnets E and F by means of the block b and to magnets G and H by brushes as c which rub on annular collectors d and d' respectively.

Circular rings e f g h are respectively

connected to sun gears E¹ F¹ G¹ H¹ forming 50 the armature of magnets E. F. G. H.

On the upper part of the apparatus is located a lever I pivoted on a pin i which carries also a toothed segment j engaging with a similar segment j' pivoted on a pin 55 i' located at the lower part of the apparatus, as shown in the drawings, so that by actuating the lever I, the two pins will turn simultaneously. Said two pins have, on a part of their length, a cam-shaped cross section 60 and such parts pass through collars L diametrically opposed to each other and fixed on a ring l which may be moved to the right or to the left, according to the direction of rotation transmitted to the lever I. 65 Hence the said ring may be brought close to the armature e which then engages the magnet E with which it may become connected by friction. The lever I carries a spring piece m acting as a pawl on the 70 toothed part of a fixed toothed segment m' and as a locking device when it is engaged in a recess M of said segment in resting position.

As will be seen in the drawings, the magnet G may be secured to the armature g by moving the screw n which engages corresponding recesses n' of armature g. This may be readily done by means of screw-driver engaged in a threaded hole provided 75 in the bottom of the casing and closed with a plug o.

Working, first speed.—When the motor has been started the plate D is fast to its shaft, current is sent into electro-magnets E. G. Gear E¹ is thus fixed, while the gear G¹ becomes fast to the shaft K.

The satellites P keyed on the secondary shafts B and C rotate simultaneously on themselves and around the primary shaft 80 A rolling on gear E¹ which is fixed and said satellites drive to their own speed the satellites Q fast on said shafts B and C. The latter actuate in their turn the planetary pinion E¹ which is fast to the secondary shaft K, which is thus driven at reduced speed in the same direction as the primary shaft A.

Second speed.—Current is sent into the electro-magnets F and H; the gear F¹ is thus stationary and H¹ becomes fast to the shaft K; satellites R and S enter in action 5 to produce same result as formerly.

Third speed.—Current is sent into F and G. The gear F¹ is thus fixed and gear G¹ is made fast to the shaft K: The satellites R and Q are then revolved.

10 *Fourth speed.*—Current is sent into the magnets G and H; planetary pinions G¹ and H¹ are thus made fast to the secondary shaft K and satellites S and Q act as a carrier, as they cannot rotate with their 15 planetary pinions, since the engaging pair is not in same ratio.

Accordingly, the secondary shaft K rotates at same speed as shaft A. In short, this fourth speed is obtained in direct 20 engagement and all pinions are stationary relatively to each other and their only effect is to increase inertia of the driving fly wheel.

Braking-effect.—A progressive current is sent into the fixed magnets E and F, and 25 this acts progressively on plates e and f to produce a braking effect.

Rear working.—Rear working is obtained by sending current into magnets E and H; gear E¹ is fixed, pinion H, is fast to shaft 30 K; the satellites S are fast with the satellites P and they exert a reaction on gears H¹ which are obliged to rotate in opposite direction to the primary shaft A, driving the secondary shaft K in its movement.

35 *Emergency speed.*—If the source of electric power fails for any reason, screws n are driven into their recesses n¹: they act thus as keys between the magnet G and its armature g so that they become fast; after the 40 motor has been started, the lever I is operated so, as to rotate shafts i and i' and these in their movement, apply progressively the ring l against armature e and then against magnet E, which produces a clutching effect 45 sufficient to start and drive at first speed without sliding. As soon as adherence between armature a and magnet E becomes sufficient, lever I is released and same is then held in working position by engagement 50 of pawl m with one of the teeth of segment m¹. For stopping it suffices to pull the ball of the lever I so as to disengage the pawl m from the toothed part of segment m¹ and to bring back lever I in resting position in which it is held by engagement of 55 pawl m into the recess in segment m¹.

This is the releasing operation: it frees the armature e and the pinions rotate freely without driving the secondary shaft K.

60 For this action a pedal could be used instead of the lever I.

Combining the numbers of teeth into engagement, any succession of speeds can be obtained, as in the similar mechanisms.

65 During electrical working, a rheostat

placed on circuit of the magnets enables the desired progressivity and suppleness to be obtained when passing from one speed to another.

The device hereinbefore described offers 70 many advantages.

Transmission of motion is silent even during the speed changes which are made without sliding as the teeth are always in mesh; the mechanical efficiency is good owing to 75 the perfect balancing of driving-couple, to the large working surfaces of the teeth which need no beveled edge, to the immobility of the pinions in relation to each other in the case of direct engagement and consequently wear is reduced to the minimum. The whole can be very easily adapted to the motor to form the arrangement called "monobloc" while the shaft A may be an extension of the crank shaft of the motor. 80

It is to be noted that the periphery of plate D may be toothed to drive at desired ratio a pinion d which may control an electric dynamo or any other accessory. A pinion as d, actuated by an auxiliary starting motor, may also be used for automatic starting of the driving shaft without other intermediary transmission. As will be readily understood, this mechanism is more especially suitable for motor-cars, but it may be generally resorted to in many other cases. 85

Claims.

1. A change speed gear comprising a drive shaft, a driven shaft, a frame having bearings for said shafts, two pairs of sun gears of different diameters loose on said drive shaft and revoluble independently of one another, an element fast to the drive shaft and having bearings, intermediate shafts mounted in said bearings of said element and having pairs of planet gears of different diameters at their ends and which respectively engage the sun gears, armatures, one of which is secured to each of the sun gears for rotation therewith, fixed electro-magnets for coaction respectively with the armatures of the sun gears of one pair, electro-magnets arranged for rotation with the driven shaft for coaction respectively with the sun gears of the other pair, means to lock one of said armatures to one of said revolubly mounted electro-magnets, and mechanically actuated braking means for one of the armatures which coacts with the fixed electro-magnets. 100

2. A change speed gear comprising a drive shaft, a driven shaft, a frame having bearings for said shafts, two pairs of sun gears of different diameters loose on said drive shaft and revoluble independently of one another, an element fast to the drive shaft and having bearings, intermediate shafts mounted in said bearings of said element and having pairs of planet gears of different diam- 105
